J. P. BRENNAN

SIGN HOLDER FOR AUTOMOBILES

Filed Oct. 9, 1925

INVENTOR.

Joseph P. Brennan.
By J. H. Weatherford

ATTORNEY-

UNITED STATES PATENT OFFICE.

JOSEPH P. BRENNAN, OF MEMPHIS, TENNESSEE.

SIGN HOLDER FOR AUTOMOBILES.

Application filed October 9, 1925. Serial No. 61,596.

My invention relates to a sign holder adapted to be secured to the filling tube of an automobile; and especially to such a holder that may be easily and quickly placed 5 and secured on the filling tube; that will not interfere with the use of the filling tube for its normal purpose; and that may be so secured to the tube as to strengthen and brace the same against the extra service required.

10 The objects of my invention are:—

First, to make a sign holder that may be quickly placed on and fastened to the filling tube, and as quickly removed.

Second, to provide means for reinforcing 15 the top of the radiator and the tube against the extra strain placed thereon; and

Third, to provide means for preventing the sign turning when in use.

20 I accomplish these objects as will be more fully, hereinafter set out in the drawings, specification and claims.

In the drawings:—

Fig. 1 is a side view of a portion of the 25 upper front end of an automobile radiator showing my invention applied to the filling tube thereof.

Fig. 2 is a fragmentary front view of the same.

30 Fig. 3 is a section full size, through the filling tube showing how the attachment is made thereto.

Referring now to the drawings in which the various parts are referred to by numerals,—

1 is the fragmentary portion of the radiator, 2, (Fig. 3) is the filling tube projecting upward therefrom. 3 is an exteriorly threaded locking sleeve, a portion of which 40 has been broken away to show the interior threads 4 of the filling tube. 5 is the filling tube sleeve, the upper portion of which is provided with interior threads 6 of the same pitch and diameter as the filling tube 45 threads 4, the lower portion being counterbored to fit over the largest outer diameter of the filling tube.

7 is a reinforcing plate for the top of the radiator which plate is shaped to conform 50 to the curvature of the radiator and has a hole therethrough to permit placing it over the filling tube, and if the base of the filling tube be larger than the top, being made to fit closely there-around. The center portion 8 of the plate 7 projects forward in 55 front of the filling tube and ordinarily be-

yond the front of the radiator and has ears or lugs 9 turned upward on both sides to form a post socket. On either side of this post socket, the front edge 10 of the plate 7 is turned downward at right angles to fit closely over the front edge of the radiator.

11 is the filling tube cap. If desired, the lower edge of the filling tube sleeve may be provided with an annular flange 12.

13 is the sign post preferably of channel iron, which post is stepped in and supported by the post socket. This post is secured to the filling tube sleeve 5 by two circumferential bands or clamps 14, preferably of thin metal, which have ears 15 which are clamped to the sign post, and secure the post to the filling tube sleeve, by bolts 16 which pass through the said ears and the post.

17 is the frame for the sign and 18 the sign, the bottom and sides of the frame being preferably channels and the top, two flat bars which permit a sign to be inserted or removed through the top.

To attach the device to the automobile 80 radiator, the filling cap 11 is removed and the locking sleeve 3 screwed into the filling tube. The reinforcing plate 7 is then dropped into place and the filling tube sleeve 5 screwed firmly down over the locking sleeve until the plate 7 is clamped firmly against the top of the radiator, after which the filling cap may be replaced and removed as may be desired or necessary.

The bolts 16 are then loosened and the 90 bands or clamps 14 are slipped over the filling tube sleeve and the bolts again tightened to securely clamp the sign post to the post sleeve.

It will be seen that the post socket forms 95 a secure footing for the post and that when clamped the bands 14 not only hold the sign post securely, but also lock the post sleeve against unscrewing.

It will also be seen that when in place 100 the filling tube sleeve and plate reinforce the radiator top and the filling tube and assist in taking the strains imposed thereon by the sign. The post socket also prevents the sign turning, and distributes any strain 105 from such turning to a large area of the radiator entirely eliminating twisting strains on the filling tube.

While this description is confined to an 110 interiorly threaded filling tube it will be distinctly understood that it may similarly be used with slight modifications on an ex-

teriorly threaded tube, and that it is not intended to confine the use of this device to such interiorly threaded tube.

Having now fully described my invention, what I claim and desire to secure by Letters Patent in the United States, is:—

1. In a sign holder for an automobile, having a radiator and filling tube; the combination with a reinforcing plate adapted to 10 surround the filling tube and rest on and conform to the upper surface of the radiator, said plate having a downwardly turned edge adapted to engage the front edge of the radiator, and a post socket, a sleeve surrounding said filling tube and clamping said plate against said radiator surface, a locking sleeve engaging said filling tube sleeve and filling tube, a sign frame, a post therefor adapted to be stepped in said socket, and 15 clamps securing said post to said filling tube sleeve.
2. In a sign holder for an automobile, having a radiator and filling tube; the combination with a reinforcing plate adapted to 20 surround the filling tube and rest on and conform to the upper surface of the radiator,

said plate having a post socket, a sleeve surrounding said filling tube and clamping said plate against said radiator surface, a locking sleeve engaging said filling tube sleeve and filling tube, a sign frame, a post therefor adapted to be stepped in said socket, and 30 clamps securing said post to said filling tube sleeve.

3. In a sign holder for an automobile, having a radiator and filling tube; the combination with a reinforcing plate adapted to 35 rest on and conform to the upper surface of the radiator, said plate having a downwardly turned edge adapted to engage the front edge of the radiator, and a post socket, a sleeve surrounding said filling tube and clamping said plate against said radiator surface, a locking sleeve engaging said 40 filling tube sleeve and filling tube, a sign frame, a post therefor adapted to be stepped in said socket, and clamps securing said post to said filling tube sleeve.

In testimony whereof I have hereunto set my name.

JOSEPH P. BRENNAN.
